UNITED STATES PATENT OFFICE.

HARRY L. WILLIAMS, OF LAKEWOOD, OHIO, ASSIGNOR TO THE WILLIAMS PIVOT SASH COMPANY, OF CLEVELAND, OHIO, A CORPORATION OF OHIO.

SWINGING-SASH WINDOW.

1,114,836.

Specification of Letters Patent. Patented Oct. 27, 1914.

Application filed December 6, 1912. Serial No. 735,291.

To all whom it may concern:

Be it known that I, HARRY L. WILLIAMS, a citizen of the United States, residing at Lakewood, in the county of Cuyahoga and State of Ohio, have invented certain new and useful Improvements in Swinging-Sash Windows, of which the following is a specification.

The invention relates to windows in which 10 the sash is vertically pivoted either in the middle or at the sides of the frame, and to that particular type of windows in which a rocking Z bar is provided on the window sill to close and lock the joint between the 15 sill and the sash when the window is closed.

The object of the invention is to provide suitable means for mounting and manipulating the rocking Z bar for a most efficient and positive performance of its functions 20 as a lock and a closure, and to prevent an accidental displacement of the bar in either its opened or closed relation; and furthermore to provide means for locking the sash when opened to various angles from its 25 closed position.

The objects of the invention thus set forth in general terms are attained by the preferred embodiment thereof illustrated in the accompanying drawings, forming part 30 hereof, in which:

Figure 1, is an inside view of a centrally-pivoted swinging-sash window showing the improved devices applied thereto; Fig. 2, a vertical section of the same on line 2—2, 35 Fig. 1; Fig. 3, a transverse section of the same on line 3—3, Fig. 1; Fig. 4, a vertical detail section showing the improved locking devices on line 4—4, Fig. 1; Fig. 5, a perspective view of the several parts of the 40 operating devices in relative position for assembling; Fig. 6, a fragmentary plan view of the window with the sill plate broken away and showing the crank disk, the pitman and the guide bar in open relation; 45 Fig. 7, a similar view showing the same parts in closed relation; Fig. 8, an under side perspective view of the closure bar.

Similar numerals refer to similar parts throughout the drawings.

50 In this class of windows, the sill bar 1 is secured on the sill proper 2, and rises above the sill stool 3, so that the lower sash bar 4 will swing free of the stool. The sill bar is provided with the longitudinal V

55 shaped channel 4 to receive the web 5 and

inner flange 6 of the closure bar, when the same are rocked downward in open position, as shown in Fig. 2; and the edge of the lower sash bar is provided with the longitudinal inverted V shaped groove 7 to 60 receive the inner flange 6 of the closure bar, when the same is rocked upward in closed relation.

A series of hinge plates 8 are recessed and secured in the bottom of the sill-bar channel 4, and are provided with the pintles 9 located slightly above the forward edge 10 of the sill bar, upon which pintles the angle 11 between the web 5 and forward flange 12 of the closure bar is adapted to rock, 70 preferably free of said forward edge; and a series of hinge plates 13 are secured to the lower side of the web 5 of the closure bar, and are provided with the bearings 14 which engage under the pintles 9 to complete the hinge joint thus formed between the forward angle 11 of the closure bar and the forward edge 10 of the sill bar. 75

The pitman 15 is composed of the plate 15^a and the adjusting bar 15^b screwed into 80 the forward end thereof. The forward end of the adjusting bar is connected with the forward flange 12, of the closure bar by the ball and socket joint 16, and the rear end of the pitman plate is laterally widened and 85 provided with the transversely elongated slot 17. The U shaped guide bar 18 is engaged by the dowel pins 19 with the sill stool, and the arms of this bar form guides for the pitman plate and serve to hold the 90 same in proper longitudinal alinement.

The disk crank 20 rests and rotates upon the curved yoke end of the guide bar as a bearing, and is provided with a central pivot post 21 on its upper side, the eccentric pivot 95 pin 22 on its lower side, and the operating arm 23 extending from one peripheral edge. The plate 24 is engaged with and secured to the sill by the dowel pins 25 and screws passed through the apertures 26. This sill 100 plate arches over the disk crank, and is provided in its under side with the bearing socket 27 for the central pivot post 21, of the disk crank; and when a centrally pivoted sash is used, as shown, the sill plate is also 105 provided with the pivot post 28 and the lock sockets 29, 29^a and 29^b, on its upper side.

The plate 30 is secured on the inner side 110 of the lower sash bar and is preferably pro-

vided on its lower end with the flange 31 extending outward under the sash, and inward as a shield covering the bolt sockets on the upper side of the sill plate. The bearing socket 32 for the pivot post 28 is provided in the lower end of the sash-plate flange 31 and forms the lower pivot bearing for the sash.

The bolt crank 33 is located on the inner side of the sash plate 30; its pivot shank 34 is journaled in the plate and extended rearward therefrom. The curved bolt 35 is mounted on the extended portion of the pivot shank, which is preferably squared to receive the bolt, and is furthermore provided with the retaining pin 36 on its free end and a spiral compression spring 37 between the pin and the bolt, to press the same against the sash plate and frictionally hold it in a given position of rotation.

When the parts are assembled the bolt is adapted to be rotated by its crank to engage its free end into one of the bolt sockets in the sill plate, to positively hold the sash at a desired angle of rotation. To increase the bearing of the bolt on the sides of the sockets, the raised ribs 38, 38^a, 38^b and 38^c are preferably provided on the sash plate between the sockets, and the first lug 38 on each side is inclined so that if the free end of the bolt should be depressed when the window is closed, the inclined rib will throw the same upward to clear the other ribs, in which position the bolt is frictionally held by the compression spring until it is forced into one of the sockets by a positive rotation of the crank. Likewise, when the free end of the bolt is disengaged from a socket, by a rotation of the crank, the bolt will be held above the ribs by the same spring while the window is being swung to and fro.

The closure bar is rocked upon its pivots from its closed to its open position and vice versa, by a rotation of the disk crank; and the parts are so proportioned and arranged that when the closure bar is rocked into open position, the operating arm 23 will stand at right angles on one side of the pitman, as shown in Fig. 6, and when the closure bar is rocked into closed position 50 the operating arm will stand at right angles on the opposite side of the pitman, as shown in Fig. 7. Furthermore, the crank-disk pivot-post is located in the axial line of the pitman, and the pivot pin is so located that 55 it will be in the same axial line when the operating arm is thrown into each of the open and closed positions, being in front of the pivot post in the open position and in the rear thereof in the closed position, as 60 illustrated in Figs. 6 and 7. From this arrangement of the parts it is evident that the closure bar will be locked when it is in closed position and also when it is in open 65 position, thus preventing an accidental rocking of the bar from its open position into the path of the sash door, without a positive operation of the operating bar.

I claim:

A window including a vertically-pivoted 70 swinging-sash, a sill-stool with a sill-bar on the outer side thereof, a Z-shaped closure bar having one angle pivotally secured on the outer edge of the sill-bar and the adjacent flange swinging in open and closed relation on the outer side thereof, and operating means for rocking the closure bar upon its pivoted angle.

HARRY L. WILLIAMS.
